(57) **CLAIM**

The ornamental design for a beverage carrier as shown and described.

DESCRIPTION

FIG. 1 is a top, front, right perspective view of a beverage carrier showing the new design;

FIG. 2 is a bottom, rear, left perspective view thereof;

FIG. 3 is a front view thereof;

FIG. 4 is a rear view thereof;

FIG. 5 is a right view thereof;

FIG. 6 is a left view thereof;

FIG. 7 is a top view thereof;

FIG. 8 is a bottom view thereof;

FIG. 9 is a top, front, right perspective view of an alternative embodiment of the beverage carrier showing the new design;

FIG. 10 is a bottom, rear, left perspective view thereof;

FIG. 11 is a front view thereof;

FIG. 12 is a rear view thereof;

FIG. 13 is a right view thereof;

FIG. 14 is a left view thereof;

FIG. 15 is a top view thereof; and,

FIG. 16 is a bottom view thereof.

The broken lines showing the remainder of the beverage carrier depict environmental structure and form no part of the claimed design.

1 Claim, 16 Drawing Sheets
